UNITED STATES PATENT OFFICE.

WILLIAM ERASTUS WILLIAMS, OF WILMETTE, ILLINOIS, ASSIGNOR TO UNION METAL PRODUCTS COMPANY, OF CHICAGO, ILLINOIS, A CORPORATION OF DELAWARE.

SIDE-PLATE CONSTRUCTION FOR RAILWAY BOX CARS.

Original application filed January 22, 1925, Serial No. 3,994. Divided and this application filed June 3, 1927. Serial No. 196,243.

The invention relates to a peculiar side plate for a railway house car and has for its object to make a water-shed of that part of the side plate forming part of the roof of the car.

Another object of the invention is to provide a side plate or cornice construction that will be simple in form, efficient in strength, and at the same time, will become a part of the water-shedding surface of the roof and will shed the water in the same manner as the roof itself is designed to do. Another object is to provide a method of making my improved side plate from the standard rolled Z bar now commonly used in structural steel work. Reference will be had to the accompanying drawings, in which:

Fig. 1 is a section through my improved side plate.

Fig. 2 is a section through the side plate, sheathing and roof construction.

Fig. 3 shows a modified form.

Fig. 4 shows another modified form.

Fig. 5 is an elevation of Fig. 2.

I prefer to make my side plate of rolled section in the form of a peculiarly shaped Z bar arranged to have an upwardly projecting substantially vertical flange 2, a downwardly and outwardly sloping web 3 and a downwardly projecting substantially vertical flange 4. The inclination of the web 3 preferably corresponds to the pitch of the roof.

The roof here shown is indicated as the main body portion 6 having a cover plate 7 for the joints of the roof sheets. These sheets may be joined to the side plate by having their outer edges turned down over the flange member 3 of the side plate, as indicated by 8, and secured thereto if desirable.

The framing of the car is indicated by posts 10 on the inside of the sheathing 11 here shown as steel sheets. The framing member and the sheathing are preferably positioned on the inside of the flange 4 of the side plate and are preferably secured thereto in any convenient manner, forming a waterproof construction. The inclined web 3 of the Z bar side plate sheds the water as readily as the roof sheds it, whereas the form of the old construction (having a horizontally disposed web) tends to retain water, snow or slush on the inwardly extending

web (especially in certain positions of the car on a side track, wherein the car sits at a tilt or an incline) forming a water pocket which promotes rust or corrosion. This situation is corrected by making the web 3 of the Z bar side plate in the inclined position as shown.

The form of roof shown in Fig. 2 is flanged (8) to be fastened directly to the Z bar side plate but other forms of roofs may be secured to the Z bar side plate by separate attaching members 12.

My Z bar may be made by passing the metal between appropriately grooved rolls or I may take an ordinary standard Z bar (having oppositely projecting parallel flanges and a connecting web perpendicular thereto) and run it through a set of bending rolls which will bend out the vertical flanges, thus producing the inclined web connection substantially in the form indicated in Fig. 4, the bending of these legs of the Z bar taking place at the points 13 and 14.

Instead of changing the angular relation of both flanges respectively, and the web, it may be desirable to retain one flange (for instance, flange 17) perpendicular to the web (16) and only alter the angular relation of one flange (for instance, flange 15) and the web 16. See Fig. 3. The roof sheet flange 8 would then be made to conform to the inclination of the flange 17.

The angular relation of the web and the flange (or flanges) may be accomplished by bending the flange, as shown in Fig. 4, or by opening up the fillet, as shown in Fig. 3, or by bending the web portion of the Z bar.

This is a division of my co-pending application Serial No. 3,994, filed January 22, 1925.

I claim:

1. In a construction of the class described, a Z bar side plate having a web inclined substantially in conformity of the pitch of the roof with vertically arranged legs on each side thereof, and the roof sheet connected to the upper vertical leg.

2. In a box car construction, a Z bar side plate having a web formed at an incline corresponding to the roof pitch and with a vertically arranged leg to which the sheathing is secured.

3. In a box car construction, a side plate substantially in Z bar form having the web

set at an incline and arranged to form a part of the water-shedding surface of the car.

4. A side plate for a box car substantially in **Z** form having the web thereof arranged to lie as part of the water-shedding surface and at an incline corresponding to the pitch of the roof.

5. A railway car side plate having a sloping web with an upwardly projecting flange on one edge thereof, and a downwardly extending flange on the other edge thereof.

6. A railway car side plate having a sloping web with an upwardly projecting flange on one edge thereof, and a downwardly extending flange on the other edge thereof, said flanges being substantially parallel.

7. In a railway car comprising a roof, a side wall, and a side plate, said side plate having an upwardly projecting flange to which said roof is attached; a downwardly projecting flange to which said side wall is attached, and a sloping web integrally connecting said flanges.

25 8. In a railway car comprising a roof, a side wall, and a side plate, said side plate

having an upwardly projecting flange to which said roof is attached; a downwardly projecting flange parallel to the first mentioned flange to which said side wall is attached, and a sloping web integrally connecting said flanges.

30 9. A box car having a **Z** bar side plate, said **Z** bar arranged with its main web sloping outwardly and downwardly and its upwardly extending flange or leg on the side toward the inside of the car, and its downwardly projecting flange or leg on the outside forming the eaves of the car; with a sheathing positioned on the inside of the 35 outside downwardly projecting flange or leg of the **Z** bar.

40 10. A box car having a **Z** bar side plate and the said side plate lying with its web sloping outwardly and downwardly forming a part of the roof shedding surface, and with the outside flange or leg of the **Z** bar extending vertically forming the eaves of the car with a sheathing positioned on the 45 inside of the eaves leg.

WILLIAM ERASTUS WILLIAMS.
